DESIGN FOR A MOTOR-DRIVEN BRUSH

William R. McGrew, Oakland, Calif.

Application February 18, 1936, Serial No. 61,229

Term of patent 14 years

To all whom it may concern:

Be it known that I, William R. McGrew, a citizen of the United States, residing at Hotel Oakland, 13th and Harrison Streets, Oakland, California, have invented a new, original, and ornamental Design for a Motor-Driven Brush, of which the following is a specification, reference being had to the accompanying drawing, forming part thereof.

Figure 1 is a top plan view of a motor-driven brush, showing my new design.

Figure 2 is a side elevational view of the brush.

Figure 3 is an end elevational view of the brush.

I claim:

The ornamental design for a motor-driven brush, substantially as shown.

WILLIAM R. McGREW.
